UNITED STATES PATENT OFFICE.

EDWARD E. KILBOURN, WILLIAM E. SMITH, AND ISAAC W. KILBOURN, OF NEW BRUNSWICK, NEW JERSEY, ASSIGNEES TO KILBOURN MANUFACTURING CORPORATION, OF NEW BRUNSWICK, NEW JERSEY.

CIRCULAR-KNITTING MACHINE.

1,087,954.

Specification of Letters Patent.

Patented Feb. 24, 1914.

Application filed March 21, 1910. Serial No. 550,784.

To all whom it may concern:

Be it known that we, EDWARD E. KILBOURN, WILLIAM E. SMITH, and ISAAC W. KILBOURN, citizens of the United States, residing at New Brunswick, in the county of Middlesex and State of New Jersey, have invented certain new and useful Improvements in Circular-Knitting Machines; and we do hereby declare the following to be a full, clear, and exact description of the invention, such as will enable others skilled in the art to which it appertains to make and use the same.

Our present invention is an improved knitting machine, the novel features of which enable the length of the stitch formed by the machine to be changed at any point in the article being knit and they also enable a machine in which movable sinkers or web holders are employed to itself "set up" or begin an article by merely introducing a thread into the machine so as to be engaged by the needles, thus saving much time in starting the knitting of any article. In case a stitch should be dropped the machine will itself pick it up and resume correct knitting.

In the drawings we have shown our invention as applied to a circular knitting machine of the general type shown in the various patents granted to Mr. E. E. Kilbourn, more especially Nos. 669,730 and 679,281.

In the patents to which reference has been made provision was made for automatically lengthening the stitches of the entire web. Our present improvements may be used in place of the devices shown and described therein or those devices may be retained and our improved means added to the machine, and the machine made to embody both forms. In such case the older arrangement of devices will be used when it is desired to lengthen the stitches entirely around the web and our present construction when it is desired to lengthen the stitches for the front or rear half of the stocking or other web.

In the said drawings, Figure 1 is a view in elevation of the left hand end of a circular knitting machine of the character already indicated without improvements embodied therein. Fig. 2 is a like view of part of the rear of such a machine. Fig. 3 is a partial front view. Fig. 4 is a vertical section of the needle cylinder. Figs. 5

and 6 are views of the needle jacks used with the upper cam cylinder. Fig. 7 is a view of the needle jack of the lower cam cylinder. Fig. 7^a (Sheet three) is a detail view showing three flat wire needles corresponding to those shown in Figs. 5, 6 and 7, but drawn to a smaller scale. Figs. 8 and 9 are views of two different forms of movable sinker or web holder forming a part of our machine. Fig. 10 is a partial inside view of the upper cam cylinder. Fig. 11 is an under side view of parts shown in Fig. 10. Fig. 12 is an outside view of the parts shown in Fig. 10. Fig. 13 is a view showing a detail of the cam construction shown in Figs. 10 to 12 inclusive. Fig. 14 is a plan view of the means for causing the knitting cam to vary the lengths of stitches. Fig. 15 is a view in perspective of the pattern wheel and connections for changing the position of the knitting cam. Fig. 16 is an inside view of a bracket secured at one side of the cam cylinder and devices connected therewith. Fig. 17 is a view of the outside of said bracket. Fig. 18 is a transverse section of the devices shown in Fig. 17 taken on line $x-x$ Fig. 17. Fig. 19 is a section of said bracket on line $y-y$ Fig. 17. Fig. 20 is a top or plan view of said bracket. Fig. 21 is a partial horizontal section thereof. Fig. 22 is a detail view showing a certain relative relation of the bracket and a lever operating in conjunction therewith. Fig. 23 is a sectional view taken on line $z-z$ Fig. 22. Fig. 24 is a detail view of the parts shown in Fig. 22 in a different position. Fig. 25 is a sectional view on line x^4-x^4 Fig. 24. Fig. 26 is another view of same parts. Fig. 27 is an enlarged plan view of the part of the cam cylinder shown in Fig. 14. Figs. 28, 29 and 30 are sectional views illustrating details of the cam cylinder and connected parts. Fig. 31 is a partial view on an enlarged scale of the inside of the lower cam cylinder. Fig. 32 is a like view of the outside of the same parts. Fig. 33 is a top or plan view of the lower cam cylinder. Figs. 34 and 35 are sectional views showing details of construction. Fig. 36 is a partial under side view of same cylinder.

In the machine shown in the drawings, A is the main or power shaft, extending longitudinally of the machine beneath the bed plate of the same. B is a shaft extending

transversely of the bed plate of the machine and is connected by gearing with the cam cylinders to give them a constant rotary motion during circular work and a reciprocating motion to the upper cam cylinder during reciprocating work, as fully described in the patents hereinbefore referred to.

The needle cylinder C is of the general form shown in said patents, but at c^o is provided with a circumferential notch or groove in which is located a small spiral spring band C' for holding the needle jacks elastically in the grooves of the cylinder.

The needle jacks used in the machine are of the form shown in Figs. 5, 6 and 7. Of those shown in Figs. 5 and 6, c and c' are those operated by the upper cam cylinder, while the jacks c^2 are connected with the needles operated by the lower cam cylinder. Each of these jacks is provided with the rebounding shoulder or incline c^3 which, when the needle is depressed by the knitting cam, is brought down against the spring band C'. When the nibs of the needles are engaged by the riser cam incline thereafter the spring band acting on the incline tends to raise the jack and needle thereby aiding in the initial movement of the jacks and needles upward. The jacks c , c' are also provided with inclined rebounding shoulders c^4 , c^4 and the jacks c^2 with the shoulder c^5 . These shoulders engage the spring band C' when moved to their highest point upward in knitting and the spring band in like manner assists the initial downward movement. This construction is of very material advantage, and enables the machine to be run at a higher rate of speed than is possible without it.

The fashioning needle jacks c are formed with the notch or recess c^6 below the shoulder c^4 . When these needles are raised out of operative position in narrowing, the shoulder c^4 passes under the band C', the spring enters the recess c^6 and holds the jacks and needles in their elevated position until depressed to their active position in the operation of widening. In addition to these forms of needle jacks, others of like construction having longer or shorter nibs may be employed, common in knitting machines of various forms for various purposes. This feature of varying the length of the nibs of jacks or needles, is of such common use that illustration and particular description thereof and designation by reference letter is unnecessary. It is to be understood that the narrowing and widening mechanism of our present machine is substantially the same as that shown and described in the said patents. In place of needle jacks as described, we may employ flattened wire needles having the inclines and shoulders referred to, as shown for example in Fig. 7a, Sheet 3.

To the upper end of the needle cylinder is secured the bed D and cam disk T for a

series of movable sinkers or web holders t alternating with the needles of the needle cylinder in the usual way. These web holders are of the form shown in the drawings and described hereafter.

70

In the patents hereinbefore referred to, two cam cylinders are employed. We provide our improved machine with a like number, the upper cam cylinder as in the machine shown in the patents, knits the back half of the stocking and the lower cylinder knits the front half. While for convenience the term "half" is used to designate the part knit by the upper and lower cam cylinders, it is to be understood that this term does not limit the applicants to an exactly equal division of the needles between the cams as it may some time be found advisable to have a greater number of needles in one cylinder than the other. In the drawings K is the upper cam cylinder and K' the knitting cam connected therewith, see Figs. 10 and 12, and K² is the needle supporting ledge. The cam K' is secured to a block k movably supported in a recess in the cam cylinder. A strip k' on the top of the cam cylinder extends across the recess in which the block k is placed and is secured firmly to the cam cylinder by screws k², k². To the block k below the cam K' is secured the plate k^{2x} which forms the lower part of the needle cam groove below the cam K' and the lower part of the riser cams k³, k⁴. At its inner side the plate k^{2x} is provided with flanges k⁵, k⁵, see Fig. 11, extending on each side, and between these flanges and the block k are placed reduced portions of the plates k⁶, k⁷ which are cut away at the upper part of the same to form the upper part of the riser cams. These plates are secured to the inside of the cam cylinder and the reduced portions form a guide for the block k in its movements to vary the position of the cam K'. A bolt k⁸ passes through the strip k' and is secured to the block k. A spiral spring k⁹ extends between the head of the bolt k⁸ and the strip k' and serves to hold the block k and the cam in an elevated position against the strip. In this position the cam will only draw down the thread to form the shortest stitches made by the machine except this be changed by the raising of the nosing.

It will be seen that the flanges k⁵, k⁵ overlap the edges of the plates k⁶, k⁷ and avoid the forming of a fissure or line of division directly across the bottom of the cam groove that might be engaged by the nibs of the needle jacks. The inner upper corners of the reduced portions of the plates k⁶, k⁷ are cut away or rounded to prevent these parts from presenting a sharp shoulder when the cam K' is moved downward and the upper outer corners of the flanges k⁵, k⁵ are also rounded or cut away in the same manner.

180

The cam K' is depressed to increase the length of stitch by the following instrumentalities.

To the outer side of the block k is secured the arm or projection k¹⁰ the outer end of which is provided with inclines k¹¹ and k¹². At one side of the projection k¹⁰ a lever L is pivoted to the cam cylinder, at l to a plate or bracket L', secured to the outer side of the cam cylinder. See Figs. 14, and 22 to 27.

Adjacent to the smaller end or head l¹ of the lever L, two bolts or screws l¹ l² pass downward through threaded apertures in the lever L. These bolts or screws have their lower ends rounded and are in such a position that when this end of the lever is thrown inward they will impinge upon the inclines k¹¹ and k¹² of the projection k¹⁰, and move the cam K' downward. The bolt or screw l¹ is in line with and will engage the incline k¹¹ and the bolt or screw l² is in line with and will engage the incline k¹². These bolts or screws are each provided with a cramp or jam nut l³ to hold them firmly in the position to which they may be turned.

On the stationary flange surrounding the base of the upper cam cylinder is mounted a bracket M, see Figs. 16 to 26 inclusive. This bracket is provided with two vertical slots in which are movably mounted blocks m, m'. The block or slide m is shorter than the slot in which it is placed and a spring m² is placed beneath it holding it normally in the upper part of the slot and against the plate m³ secured to the top of the bracket. The block or slide is held within the slot by the plate m⁴ secured to the outer side of the block or slide and extending on each side of the slot and by the knocker cam m⁵ secured to the inner side of the slide.

The block or slide m' is in like manner shorter than the slot in which it is mounted and is normally held in the lower part of the said slot by a pin n inserted in said block or slide. Said pin extends outwardly and engages a cam slot n' in a plate n² secured to a slide N, which is movably mounted on the base of the bracket M by screws or pins n⁴, n⁴ passing through horizontal slots n³, n³ into the base of the bracket. The block or slide m' is provided with or has secured to it on its outer side, a retaining plate m⁶ and on its inner side the two knocker cams m⁷, m⁸. The cam m⁷ has two cam grades the lower one m^{7x} extends outward a less distance than the cam grade m⁷.

The outer end of the shaft B is provided with means to actuate a pattern cylinder H through pawls h and h' and ratchet h², secured to the said cylinder. The pattern cylinder is mounted on a shaft H' and gears with a spur gear I on a pattern wheel I'. The arrangement is such that the pattern wheel makes one entire revolution during

the knitting of a single stocking, and as set forth in the patents to which reference has been made, this pattern wheel brings about certain changes in the operation of the machine.

In addition to the features of construction shown in said patents, the pattern wheel is provided with an outwardly extending flange i^x and risers i are provided which may be placed on the inner side of said flange so that at the time desired they will engage one arm of a bell crank lever i'. The other arm of the bell crank lever is pivoted to a link i², see Figs. 1, 2, 3 and 15. The link i² is in turn pivoted to an arm j secured to a rock shaft J mounted in bearings secured to the top of the bed plate of the machine. The shaft extends rearwardly to near the rearward side of the machine and is there provided with an arm j' connected by a link j² to an arm j³ of a rock shaft J', extending longitudinally of the machine at the back of the same. Near the opposite end of the shaft J' an arm j⁴ is secured thereto. Said arm j⁴ extends upwardly and at its upper end has an eye through which is passed a rod or link j⁵. A spring j⁶ surrounding the rod bears against the inner side of the arm j⁴ and the opposite end of the spring bears against a collar j⁷ on the rod j⁵ which, in this instance, is secured in place by a cotter j⁸. A cotter j⁹ passes through the rod j⁵ on the outer side of the arm j⁴. The other end of the rod j⁵ is pivoted to a pin n⁷ secured to the slide N. The rock shaft J' has secured thereto a coiled spring j¹⁰ surrounding the same and so connected to the shaft and to the frame of the machine, that the said spring tends to move the arm j⁴ and rod j⁵ outwardly drawing the slide N in such position that the pin n of the slide m' will be in the lower part of the cam slot n' in the cam plate n². The spring also through the connections j³, j², j, rock shaft J and arm j', link i², holds the lever i' in contact with the inner side of the flange i^x on the pattern wheel I' or against the risers when they are brought in contact with said arm. It will thus be seen that the slide N is moved in both directions by spring pressure which enables the slide N to be operated in a satisfactory manner without the extreme nicety of adjustment of its connections with the pattern wheel that would be otherwise required.

In knitting circular work the lever i' ordinarily engages the inner side of the flange on the pattern wheel and the knocker cams m⁷ and m⁸ are in their lower position. The cam cylinder rotates in the direction of the arrow Figs. 22 and 24 to bring the head of the lever L to the bracket M before the tail of the same.

Assuming that the head of the lever L is in its most outward position and the block

70

80

85

95

105

110

115

120

125

130

- or slide m' is in its lower position, with the lever i' bearing against the inner face of the flange i^2 , on a forward movement for circular work, the head of the lever will engage 5 the cam m^5 slightly above the point of the same and pass over the cam, depressing the latter against the pressure of the spring m^2 , which when the lever has passed beyond the cam, will return the cam to normal position.
- 10 The head of the lever in such case will not come in contact with the cams of the block or slide m' . The tail of the lever being in a higher horizontal plane will take the course indicated by the arrow and dotted line in Fig. 24 and will come in contact with the knocker cam m^7 . The tail l^2 of the lever will then be forced inward throwing the head l^2 outward, freeing the knitting cam from the pressure of the screws or tappets 15 l^1, l^2 which will thereupon be raised by the spring k^9 to its highest position as shown in Fig. 28 to knit a short stitch. Thereafter the lever during the operation of the cam cylinder will take the course indicated by the arrow 1 and dotted line in Fig. 22 and will not be moved as it passes the bracket M. Should the lever i' now engage a riser i on the pattern wheel I', this lever through its connections will move the slide N to bring 20 the pin n into the upper horizontal part of the slot n' . This will raise the slide m' with the knocker cams m^7 and m^8 into its higher position. The continued forward movement of the knocker cam cylinder will move the head of the lever L over the cam m^6 , as before described, and will bring it in contact with the knocker cam m^8 which will throw the head of the lever inward bringing the bolt or tappet l' into engagement with the 25 incline k^{11} , depressing the knitting cam.
- 30 The plate or bracket L' adjacent to the head of the lever L, is provided with a boss l^7 in which is mounted the spring bolt l^7 . The spring tends to force the upper end of this bolt against the underside of the head 35 of the lever L and the lower face of the tail is provided with a recess shown in Fig. 12 with which the bolt engages when the said lever is moved by the cam m^8 engaging the head of the lever, in which case the parts 40 will be in the position shown in Fig. 29, that is, when the lever has been moved to cause the tappet l' to engage the incline k^{11} . The engagement of this bolt with the recess will 45 hold the lever from accidental displacement.
- 50 The lever may be provided with recesses of like character to be engaged by the bolt when the lever has been moved to the other positions described if preferred, but it has been found that this is not necessary as the lever will remain in the other positions to which it is moved without any retaining means.
- 55 In knitting ladies' hose, on beginning the stocking at the top of the leg, the pattern

wheel will raise the nosing C^x which forms the upper end of the needle cylinder and give a lengthened stitch entirely around the web. This continues until the calf has been knitted when the stitch is gradually shortened until the normal length is reached as explained in the patents to which reference has been made.

In case the stocking is to be strengthened or spliced on the back, at the point that the additional thread is thrown in, a riser i on the pattern wheel raises the lever i' and moves the slide N to raise the cams m^7 and m^8 to their higher position. The continued revolution of the cam cylinder will cause the lever L to assume the middle position as just explained, lowering the knitting cam K' and lengthening the stitch. This continues until the beginning of the narrowing operation for knitting the heel.

At the close of circular work the cam cylinder is left in a position in which on the first reverse movement the lever L will pass the bracket M. As the tail l^2 of the lever passes the bracket M it passes under the cam m^7 and the lever is not moved. The head l^2 of the lever, however, engages cam m^5 and is thrown into its most inward position, the pin l^2 engaging and passing the incline k^{12} to the position shown in Fig. 30 and depressing the knitting cam K' to its lowest position. The position of the bracket M is such that the lever L will not come into engagement with the cams of the bracket during the remainder of the reciprocating knitting for the toe or heel.

If the bottom of the stocking is to be reinforced the slide N is maintained in position to keep the cams m^7 and m^8 in their higher position, and as circular knitting is resumed the lever L is again carried past the bracket M and the tail of the lever engaging the cam grade m^{7x} the lever is thrown into the position occupied by it during the splicing of the back of the ankle, causing the upper cam cylinder to knit a stitch of the same length as during the splicing operation. This is continued until the toe is reached when the stitch will be again lengthened as in knitting the heel. That is to say on the first reversing movement the head l^2 of the lever L strikes cam m^5 (see Fig. 26) pushing the head in to its fullest extent and setting the cam for the longest stitch, as in the case of the heel.

When the toe is completed, it is to be noted, the machine must be placed in position to knit the upper part of the leg of another stocking and with the tightest stitch. At this point therefore, the lever i' passes from the riser or series of risers i and causes the knocker cam slide m' to drop to its lower position. This brings the cam m^7 in the plane of the tail l^2 of the lever L, and on resuming circular work the tail l^2 strikes

cam m^1 , and throws the head l^x to its outermost position thus allowing the knitting cam to return to its highest position for knitting the shortest stitch.

5 In order to make the operation of the knocker cams and lever L more easily understood we will briefly recapitulate the various positions of the same during the knitting of a stocking.

10 1. *Knitting leg with tight stitch.*—Head l^x of lever in outermost position, knocker cams in lower position, head l^x strikes, depresses and passes over knocker cam m^5 in each course. (Fig. 22.)

15 2. *Knitting leg with high splice above heel.*—Knocker cam slide is raised by pattern mechanism, head l^x strikes knocker cam m^8 and pushes head half in, lowering knitting cam and lengthening stitch, head l^x

20 continues to depress and pass over knocker cam m^5 in each course, but tail l^x will merely pass under knocker cam m^7 (Fig. 24). As this knitting cam only operates the needles for the back of the stocking the stitch remains as set during the complete revolutions of the cam cylinder.

25 3. *Knitting heel.*—On first return reciprocating movement the head l^x strikes knocker cam m^5 and is pushed in to greatest extent depressing knitting cam to set longest stitch. The tail l^x is now in outermost position but does not strike any of the cams during reciprocating work. (Fig. 26.)

30 4. *Knitting sole.*—The knocker cam slide still being in elevated position, on resuming circular work after knitting heel tail l^x strikes knocker cam m^{1x} and throws head l^x to median position setting knitting cam for sole stitch. (Fig. 24.)

35 40 5. *Knitting toe.*—On first reciprocation head l^x strikes knocker cam m^5 and is moved in to greatest extent,—setting extra long stitch for toe; after the toe is knit slide m is lowered, and on resuming circular work 45 to commence leg of next stocking, the tail l^x strikes the cam m^1 throwing head l^x all the way out, and setting knitting cam for the short or tight stitch.

45 The lower cam cylinder O is in like manner provided with a movable knitting cam O', see Figs. 31 and 32 and this cam is provided with an outwardly extending projection having like inclines. The cylinder has also a lever P which is a counterpart of the lever L and is operated by a bracket P' having cams m^1 and m^8 similar to those of the bracket M. The bracket P' does not have the cam m^5 as this cam cylinder is never reciprocated, and for this reason the gear by which it is operated is rigid with the cylinder as there is no necessity for providing for lost motion. The cams of the bracket P' are raised and lowered by a slide Q which is operated in a manner similar to the slide N by devices connecting it with the pattern

50 wheel I'. In this lower cam cylinder, o is the needle supporting ledge. A little in advance of the knitting cam O' this ledge is cut away to a lower level o' and a cam R engages and depresses the nibs of the needles to the lower level.

55 A riser cam R' is movably mounted in the cylinder with its uppermost point normally below the level o'. The cam R' is, in this instance, secured to a block r which has a part r' extending upward inside of the gear teeth of the cylinder but outside of that part of the cylinder extending above the said teeth. This upwardly extending part is provided with an outwardly extending projection r² from which extends an arm r³. The part r² at one side of the same is formed with two inclines or bevels r⁴, r⁵. Adjacent to this side of the part r² is a spring pressed slide S which is provided 80 with a pointed or double inclined end s extending toward the part r² but passing by the extreme end adjacent thereto. In the position shown in Figs. 34 and 32 the slide holds the cam R' from being moved accidentally from its lower position. When the cam R' is raised the incline r⁴ engages the end s of the slide and forces it back against the tension of its spring. When the cam R' has reached its higher position the 85 spring forces the end s of the slide S beneath the part r² and into engagement with the incline r⁵ and holds the cam in the position to which it has been moved. The cam R' can be raised or lowered by hand or automatic means controlled by the pattern cylinder or a pattern wheel may be employed for the purpose.

90 The cam R' is of less thickness than the cams R and O'. The ledge o' is of sufficient height to enable the needles resting thereon to take the thread from the main thread guide. By supplying a splicing thread carried at a higher elevation than the main thread, and employing needles 10 having nibs of different lengths any given portion of the front of the stocking can be spliced or reinforced with the appropriate length of stitch. In doing this such needles as are not to take the reinforcing thread are provided with nibs of a length that will not engage the cam R' when raised and those that are to take the reinforcing thread will be provided with a longer nib to engage the cam R'. 11

115 Whenever the cam R' is raised to its higher position the needles with the longer nibs will be raised by the cam sufficiently to take the splicing or reinforcing thread and when moved downward by the knitting cam O' will also take the main thread and knit them together into the web. In such case the cam O' will be depressed by the lever P and its controlling device to lengthen the stitch. These parts will be 12

arranged to be called into action when for any purpose it is desired to lengthen the stitches on the front of the leg of the stocking, for example when it is desired to throw in an additional thread to strengthen the web at the knee of children's stockings.

The devices for moving the cam of the lower cylinder are most clearly shown in Fig. 15. To automatically control this cam 10 the pattern wheel is provided with an additional flange i'' or the flange i' is made of double width to which risers i^o may be secured in such positions as to move the lever P when desired through the connecting 15 mechanism. Such mechanism in this case is the bell crank lever i^o , link j^{o2} , rock shaft J^o , with its arms j^o , j^{o1} , link j^{o2} , rock shaft J^{o1} , its arms j^{o3} and j^{o4} , and rod or link j^{o5} connected with slide Q , the same being 20 merely a duplication of the devices for actuating the cams for moving the lever L .

What we claim and desire to secure by Letters Patent is:—

1. In a circular knitting machine, the 25 combination with a circular series of needles, a plurality of independent cams each of which operates a number of consecutive needles of the circular series of needles, said cams being capable of operating all of said 30 needles by conjoint operation, and independently actuated means for adjusting each of said cams to change the length of the stitches formed by the needles operated thereby.

35 2. In a circular knitting machine, the combination with two independently operable cam cylinders each provided with a knitting cam, one of said knitting cams operating the needles for knitting the back 40 portion of the stocking and the other of said cams operating the needles for knitting the front portion of the stocking, and independently actuated means for changing the length of the stitches formed by 45 each of said sets of needles and the cam operating in conjunction therewith.

3. In a circular knitting machine, the combination with two independently operable cam cylinders, each provided with a 50 knitting cam, one of said cams operating the needles for knitting the back portion of the stocking, and the other of said cams operating the needles for knitting the front portion of the stocking, each of said cams being 55 provided with means for independently adjusting the length of the stitches formed by the needles operated thereby, and means for actuating said independent adjusting means conjointly to vary the length of the 60 stitches in the entire course.

4. In a circular knitting machine, the combination with two independently operable cam cylinders, each provided with a 65 knitting cam, one of said knitting cams operating the needles for knitting the back

portion of the stocking and the other of said cams operating the needles for knitting the front portion of the stocking, each of said cam cylinders being provided with means for varying the position of its knitting cam 70 to correspondingly vary the length of the stitches, and for holding said cam in its adjusted position during the entire rotation of the cam cylinder, whereby said cam or cams may be set in adjusted position and 75 rotated without affecting the operation of the needles operated by the other cam.

5. In a circular knitting machine, the combination with the stitch forming mechanism, of means for changing the length of 80 all the stitches of the web at once, means for changing the length of the stitches in one part of the web and independent means for changing the stitches in another and different part of the web, and means for independently operating each stitch changing 85 means.

6. In a circular knitting machine for knitting stockings, the combination with the stitch forming mechanism, of means for changing the length of the stitches of the stitch-forming mechanism for knitting the front of the stocking, independent means for changing the length of the stitches of the stitch forming mechanism for knitting the 95 back of the stocking and controlling devices for bringing said stitch changing means into operation conjointly to change the length of stitches all the way around the tube, and independently. 100

7. In a circular knitting machine, the combination with two independently operable cam cylinders, each provided with a knitting cam, one of said cams operating the needles for knitting the back of the 105 stocking, and the other operating the needles for knitting the front of the stocking, means for adjusting and holding the cam for operating the needles which knit the back of the stocking in a plurality of different vertical positions, to lengthen the stitches to different extents during the knitting of the leg, heel, sole, and toe, whereby said adjusting means may be operated and permitted to remain in adjusted position for a 110 plurality of courses without affecting the needles which knit the front portion of the stocking.

8. In a circular knitting machine for knitting stockings, the combination with the 115 stitch forming mechanism of means for enlarging the gage of the stitches formed by the stitch forming mechanism for the rear part of the leg, independent means for enlarging the gage of stitches produced by the 120 stitch forming mechanism for the front of the leg, means for actuating said stitch enlarging means for the back of the leg, when knitting the portion thereof above the heel, means for actuating said stitch enlarging 125 130

means to a greater extent during the knitting of the heel pocket and means for actuating both of said stitch enlarging means to enlarge the stitches of both stitch forming mechanisms for front and rear of the stocking, when knitting the portion of the foot adjacent to the toe pocket.

9. In a circular knitting machine, the combination with a circular series of needles, a 10 cam cylinder, a cam carried thereby for engaging a number of consecutive needles only of said series, a second cam cylinder, a knitting cam carried thereby for engaging only the needles not operated by the other cam, 15 means for depressing one of said cams into and holding it in a plurality of different positions other than its normal position, whereby the needles operated thereby can be made to knit a normal stitch and stitches of a 20 plurality of different sizes, according to the adjustment of the cam, without affecting the operation of the other needles, and whereby said adjustable cam may be completely rotated in any position to which it may be 25 adjusted without affecting the needles operated by the other cam.

10. In a circular knitting machine, the combination with a circular series of needles, of a cam cylinder, a vertically adjustable 30 knitting cam carried thereby, a plurality of devices for depressing said cam to different extents, means for bringing one or other of said devices into operative relation with the cam, a certain number of consecutive 35 needles of said series being provided with nibs for engaging said cam, an independently operable cam cylinder, a knitting cam carried thereby, the consecutive needles of the series not operated by the first mentioned cam being provided with nibs for engaging the said second mentioned cam, and independent means for vertically adjusting said second cam to change the length of the 40 stitches formed by the needles operated thereby.

11. In a circular knitting machine, the combination with a series of needles, of a cam cylinder provided with a downwardly and upwardly extending groove for engaging the nibs of the needles actuated thereby to lower and raise the same, to effect the formation of a stitch, the portion of said cam cylinder forming the upper edge of said groove, and portions of the lower edge 50 of said groove being simultaneously vertically adjustable, and said movable portions forming the lower edge of said groove, being provided at each side of the lowest part of the groove with portions overlapping contiguous stationary portions forming part of the lower edge of said groove, to facilitate the passage of the needle nibs across the meeting edges of said fixed and movable portions of the cam.

65 12. In a circular knitting machine, the

combination with a series of needles, of a knitting cam provided with a depressing cam grade, and an elevating grade, said depressing grade being vertically adjustable, and the portion of the elevating grade adjacent to the lowest portion of the depressing grade being vertically adjustable, the fixed and movable portions of the elevating grade having overlapping portions, to facilitate the passage of the needle nibs from the adjustable portion to the fixed portion of the elevating grade.

70 13. In a circular knitting machine, the combination with a series of needles, of a knitting cam provided with a depressing cam grade, and an elevating grade, said depressing grade being vertically adjustable, and the portion of the elevating grade adjacent to the lowest portions of the depressing grade being vertically adjustable, the fixed and movable portions of the elevating grade having overlapping portions and said overlapping portions having their upper edges adjacent to their end portions beveled to facilitate the passage of the needle nibs from the adjustable to the fixed portion notwithstanding the adjustments of the cam.

75 14. In a circular knitting machine, the combination with a knitting cylinder, a series of needles therein, a cam cylinder, a vertically movable block in said cylinder, a depressing cam secured to said block, an elevating cam having fixed portions secured to said cylinder and adjustable portions secured to said block, the adjustable portion having its lateral edges lapping the adjacent edges of the stationary portion of the elevating cam, means for depressing said block in the cam cylinder and means for restoring said block to normal elevated position.

80 15. In a circular knitting machine, the combination with a knitting cylinder, a series of needles therein, a cam cylinder, a vertically movable block in said cylinder, a depressing cam secured to said block, an elevating cam having fixed portions secured to said cylinder and adjustable portions secured to said block, the adjustable portion having its lateral edges lapping the adjacent edges of the stationary portion of the elevating cam, means for depressing said block in the cam cylinder, and means for restoring said block to normal elevated position, a plurality of actuating devices for depressing said block to a plurality of different positions and pattern mechanism for controlling the operation of said actuating devices.

85 16. In a circular knitting machine, the combination with a cam cylinder, of a needle depressing cam carried thereby, and adjustable vertically to form stitches of different lengths, a horizontally movable lever, mounted on said cylinder and provided with means for depressing said cam, a vertically yielding knocker cam located on a stationary 90

part of the machine in the path of a part of said lever, for actuating said lever when the cam cylinder is moved in one direction, said knocker cam having a grade to engage 5 said lever and depress the knocker cam when the cam cylinder is moved in the opposite direction.

17. In a circular knitting machine, the combination with a cam cylinder, of a 10 needle depressing cam carried thereby, and adjustable vertically to form stitches of different lengths, a horizontally movable lever, mounted on said cylinder and provided with means for depressing said cam, a vertically 15 yielding knocker cam located on a stationary part of the machine in the path of a part of said lever, for actuating said lever when the cam cylinder is moved in one direction, said knocker cam having a grade to engage 20 said lever and depress the knocker cam when the cam cylinder is moved in the opposite direction, a separate vertically adjustable knocker cam mounted on a stationary part 25 of the machine for engaging said lever when the cam cylinder is moved in a direction to depress said yielding knocker cam, and pattern controlled mechanism for operating said vertically adjustable knocker cam.

18. In a circular knitting machine, the combination with the needle cylinder and needles, of a cam cylinder provided with a vertically movable depressing cam, a lever mounted on the cam cylinder and provided 30 at one end with a head carrying actuating devices for moving said cam to a plurality of different positions and having a tail on the opposite side of its point of pivoting, in a different horizontal plane from its 35 head, a stationary part adjacent to the cam cylinder provided with movable devices for forcing the said head inward to different positions to bring one or other of said actuating devices into operative engagement 40 with said cam, and for engaging the tail of said lever to move said head outward to different positions.

19. In a circular knitting machine, the combination with the needle cylinder and 45 needles, of a cam cylinder provided with a vertically movable depressing cam, a lever mounted on the cam cylinder and provided at one end with a head carrying actuating devices for moving said cam to a plurality 50 of different positions and having a tail on the opposite side of its point of pivoting in a different horizontal plane from its head, a stationary part adjacent to said cam cylinder, vertically movable devices carried 55 thereby, having portions for engaging the head and tail of said lever, and pattern mechanism operatively connected with said devices for adjusting them so as to move the 60 lever and said cam actuating devices carried 65 thereby to different positions.

20. In a circular knitting machine, the combination with the needle cylinder and needles, of a cam cylinder provided with a vertically movable depressing cam, a lever mounted on the cam cylinder and provided at one end with a head carrying actuating devices for moving said cam to a plurality of different positions and having a tail on the opposite side of its point of pivoting in a different plane from its head, a stationary part adjacent to said cam cylinder, a yielding knocker cam carried by said stationary part, adapted to be depressed by said lever during circular work, and to actuate said lever when the cylinder is moved 70 reversely.

21. In a circular knitting machine, the combination with the needle cylinder and needles, of a cam cylinder, provided with a vertically movable depressing cam, a lever mounted on the cam cylinder and provided at one end with a head carrying actuating devices for moving said cam to a plurality of different positions and having a tail on the opposite side of its point of pivoting in a different plane from its head, a stationary part adjacent to said cam cylinder, a yielding knocker cam carried by said stationary part, adapted to be depressed by said lever during circular work, and to actuate said lever when the cylinder is moved 75 reversely, a vertically movable slide on said stationary part, knocker cams carried thereby for engaging the lever, and pattern mechanism 80 operatively connected with said slide.

22. In a circular knitting machine, the combination with the needle cylinder and needles, of a cam cylinder provided with a vertically movable depressing cam, a lever mounted on the cam cylinder and provided at one end with a lever carrying actuating devices for moving said cam to a plurality of different positions and having a tail on the opposite side of its point of pivoting in a different plane from its head, a stationary part adjacent to said cam cylinder, a yielding knocker cam carried by said stationary part, adapted to be depressed by said lever during circular work, and to actuate said lever when the cylinder is moved 90 reversely, a vertically movable slide on said stationary part, a knocker cam on said slide for engaging the head of the lever, and moving it inward to a different distance from that to which it is moved by said yielding knocker cam, a plurality of knocker cams for engaging the tail of the lever and moving it different distances, and means for moving said slide to different positions.

23. In a circular knitting machine the 105 combination with the needle cylinder, and needles, and a cam cylinder provided with a knitting cam for engaging the nibs of the needles, of an elastic band surrounding portions of the needles, said cylinder being pro- 110 115 120 125 130

vided with means for retaining said band in engagement therewith, the portions of said needles adjacent to said band being provided with rebounding shoulders, for 5 engaging said band previous to the close of their movement in one direction to slightly distort said band, and impart an impulse in the reverse direction to the needles, the portions of the needles reciprocating within said 10 band having straight exterior edges.

24. In a circular knitting machine the combination with the needle cylinder, and needles, and a cam cylinder provided with a knitting cam for engaging the nibs of the 15 needles, of an elastic band surrounding portions of the needles, said needles being provided with rebounding shoulders, above and below said band for engaging said band and slightly distorting it previous to the close of 20 their upward and downward movements, to facilitate the reversing of the direction of movement of the needles, and to relieve the action of the knitting cam on the nibs thereof, said needles having the exterior edges of 25 the portions between the said shoulders straight.

25. In a circular knitting machine the combination with the needle cylinder and needles, and a cam cylinder provided with a 30 knitting cam for engaging the nibs of the needles, of an elastic band surrounding portions of the needles, said cylinder being provided with means for retaining said band in engagement therewith, the portions of said 35 needles adjacent to said band being provided with rebounding shoulders, for engaging said band previous to the close of their movement in one direction, said shoulders

being inclined outwardly from the vertical axis of the needle, whereby the band is 40 slightly distorted and an impulse in the reverse direction is imparted to the needles, the portions of said needles reciprocating within said band having their exterior edges straight. 45

26. In a circular knitting machine the combination with the needle cylinder, and needles, and a cam cylinder provided with a knitting cam for engaging the nibs of the needles, of an elastic band surrounding portions of the needles, said cylinder being provided with means for retaining said band in engagement therewith, the portions of said needles adjacent to said band being provided with rebounding shoulders, for engaging said band previous to the close of their movement in one direction to slightly distort said band, and impart an impulse to the needle in the reverse direction, the portions of said needles reciprocating within 60 the band having their exterior edges straight, the fashioning needles being also provided with notched portions below said shoulders for engaging said band when the fashioning needles are raised out of operation to hold 65 them in inoperative position.

In testimony whereof we affix our signatures, in the presence of witnesses.
